[57] CLAIM

The ornamental design for a stove, substantially as shown and described.

DESCRIPTION

FIG. 1 is a front elevational view of a stove, showing my new design;

FIG. 2 is a rear view thereof;

FIG. 3 is a top view thereof;

FIG. 4 is a front elevational view of a second embodiment of a stove, wherein the only difference resides in the use of a screen rather than a door.

FIG. 1

FIG. 2

FIG. 3

FIG. 4
